COIN CONTROLLED VENDING MACHINE

Milton H. Perry, East Lansing, Mich.

Application May 17, 1934, Serial No. 726,144

2 Claims. (Cl. 194—69)

This invention relates to coin controlled vending machines of the type having a delivering slide adapted to be released by the deposit and intervention of a coin so that the slide may be drawn out and the material delivered to the purchaser. This invention is especially applicable to the sale of nut kernels such as peanuts, or other small articles.

The object of this invention is the production of a vending apparatus having special construction and arrangement of its various parts, and comprising a base portion of such construction that it may be independently locked and opened to remove the deposited coin, and having a container for the goods or articles which may be attached and locked to the base by means individual in formation and independent of the locking devices of the base. By this construction means may be given one attendant to detach and fill the container when necessary, and to another person the means of unlocking the base portion to collect the coin.

In the accompanying drawings the particular construction and arrangement of the parts of this invention are illustrated.

Fig. 1 of the drawings represents a vertical section of the invention showing all parts assembled.

Fig. 2 is a horizontal section on the broken line 30 2—2 of Fig. 1.

Fig. 3 is a top view of the slide detached.

Fig. 4 is a side view of the base alone, with the outer end of the slide presented to the observer.

Fig. 5 is an enlarged vertical sectional view 35 through the base illustrating the coin chute, coin channel, and the ball stops in the recesses of the slide, a coin being indicated in broken lines.

Fig. 6 is a top view of the special implement for releasing the connection of the container with the base.

Fig. 7 is a vertical section of the special implement for releasing the container.

Fig. 8 is a top view of the individually shaped head of the screw employed to secure the top of the container to the rod connecting the container and base.

Throughout the drawings and description the same number is used to refer to the same part.

Considering the drawings, the upper portion 1 of the base carries the slide 2 in a suitable guide-way 3. At the top and bottom of the passage 3 are arranged the locking or retaining balls 4 and 5, pressed towards each other by the coil springs 6 and 7 and retained in suitable cavities formed

in the base as illustrated in Fig. 5, and retained by the screw plug 8.

In Fig. 1 is shown a center rod 9 having a lower end 10 screwed into the top of the base, and a top bore 11 for a screw 12 whereby the top 13 of the container 14 is removably secured. The top of the base portion 1 usually has a peripheral ridge 15 which forms a seat for the open bottom of the container. The containers are usually glass globular vessels open at the top and bottom 10 as shown in Fig. 1.

Projecting upwardly and outwardly from the top of the base portion 1, as shown in Figs. 1, 2 and 5, and provided with a circular coin opening 16 is the extension 17 usually made in two parts and having interiorly the coin chute 18 along which a coin introduced in the opening 16 may travel downwardly. The coin descends into the inclined coin channel 19 in the slide 2, and the channel opens at the top into the chute 18 and at the bottom into the base when the slide is pushed inwardly. In Fig. 5 the coin is shown in broken lines and marked 20. In Fig. 5 are also best shown the edge recesses 21 and 22, and in Fig. 5 it will be seen that a coin rolling down the channel 19 will reach a situation between the locking balls 4 and 5, which are somewhat greater in diameter than the recesses 21 and 22 are wide, and the coin 20 as shown by the dotted circle, when the slide is pushed in, forces the balls 30 4 and 5 out of engagement with the lock recesses of the slide allowing the slide to be moved into the position indicated by the broken lines. At this position the coin 20 is allowed to drop down into the coin receiving bottom of the base support of the container. This inward movement of the slide 2 permits the delivery of the vended material or articles from the container or globe 14 through the opening 23 in the top of base portion 1 into the dispensing and measuring opening 40 24 of the slide 2. The slide is then pulled outwardly allowing the opening 24 to deliver the article to the purchaser and into any receptacle held below the opening. To limit the outward movement of the slide, a screw 25 is placed in 45 the end of the slide and the head of the screw extends downwardly into the slot 26 of the base or housing 1 so that as the slide is pulled outwardly the head of the screw 25 strikes the end of the recess 26. If no coin is present the inward 50 movement of the slide is limited by the contact of the balls with the ends of the recesses 21 and 22.

In Figs. 1, 2 and 5 it is shown that the base support of the container consists of the upper 55

portion 1 and a lower portion 27. On one side the portion 27 is held in place by a removable pin 28 in the opening 29, and on the opposite side of the bottom 27 there is an upwardly extending 5 rib 31 which runs parallel and next to a downwardly extending rib 30 of the upper base portion 1. The downwardly extending rib has a hole 32 in alignment with a like hole 33 through the upwardly extending rib, and through those holes 10 may be introduced the hasp of a padlock of any suitable structure not shown.

The operation of this invention is believed to be made clear by the foregoing explanation. A coin being inserted by way of the opening 16 will find 15 its way between the balls, and as the slide is pushed inwardly the dispensing or article receiving space of the slide is filled from the container, and when the slide is pulled outwardly the article or nut kernels drop into the hand of the purchaser 20 held below the slide.

It will be further noted that the center rod and the individual screw lock secure the container or globe to the base, and the holder of the special implement shown in Figs. 6 and 7 may remove 25 the screw and detach the top to fill the container. Another person holding the key of the padlock

can separate the portions of the base and collect the coins in the bottom portion thereof.

Having now described this invention and the manner of its use, I claim:—

1. In a coin controlled vending machine, the combination with a base, of a slide constructed to receive and deliver an article when operated, said base having opposed spring pressed ball locks, said slide having portions constructed to engage the balls and resist inward movement of the slide when no coin is present, and said slide being constructed and arranged to force a deposited coin between the balls permitting inward movement. 5

2. In a coin controlled vending machine, the combination with a base, of a slide movable inwardly, a pair of spring pressed ball locks, said slide having portions constructed to be engaged and locked by the balls in releasable relation, said slide having a coin receiving channel, said channel being constructed and arranged to move the coin against balls during the inward movement of the slide whereby the balls move outwardly against the springs unlocking the slide. 10 20
